UNITED STATES PATENT OFFICE.

PAUL H. ROMPH, OF DETROIT, MICHIGAN.

ALUMINUM-MELTING FURNACE.

Application filed March 23, 1926. Serial No. 96,714.

The invention relates to furnace construction and more particularly to a furnace adapted for the melting of aluminum.

One of the objects of the invention is to provide a construction in which both the melting pot and the shell forming the combustion chamber are assembled as a unit and so mounted as to permit the entire unit to be tilted to pouring position. Another object is to provide in a construction of the above type an arrangement for adjustably rotating the unit so as to utilize different portions of the pot for holding the molten charge. Further objects will be apparent after consideration of the detailed construction hereinafter set forth.

In the drawings:

Figure 1 is a plan view of the furnace partly in section.

Figure 2 is a side elevation thereof partly in section.

Figure 3 is an end elevation.

Figure 4 illustrates a modified arrangement for supporting the melting pot.

1 is the aluminum melting pot of the furnace comprising a cylindrical central portion 2, the conical end portions 3 and the cylindrical pouring spouts 4. The spouts are arranged at opposite ends of the pot and are of smaller diameter than the main cylindrical portion 2 and coaxial therewith. Surrounding the pot is the cylindrical shell 5 having the end portions 6 and 7 and the cylindrical peripheral surface 8. The end portions 6 and 7 are mounted respectively on the pouring spouts 4 which latter project slightly beyond the end walls. The interior of the shell 5 is provided with heat insulating material preferably in the form of fire brick suitably secured to the shell. In order to support the furnace in such a manner as to permit tilting of the pot to a pouring position there are provided two standards 9 and 10 on opposite sides of the casing and provided at their upper ends with bearings 11 and 12. 13 is a cradle comprising a pair of semi-circular supporting members 14 and 15 connected together by the cross members 16 and 17. Centrally of each member is a laterally projecting trunnion, 18 and 19 respectively, engaging the respective bearings 11 and 12. The trunnion 18 projects through the bearing 11 and is provided with a worm wheel 20 meshing with a worm wheel 21 on a shaft

22, this shaft carrying a bevel gear 23 meshing with another bevel gear 24 on a parallel shaft 25. 26 is a hand wheel secured to the shaft 25 and adapted to operate the gearing to tilt the casing 5 and its carrying cradle to 60 pouring position.

The shell 5 is rotatable in the cradle 13 in order to adjust the same so that a different portion of the melting pot 1 may be utilized for the molten charge. For this purpose the cradle is provided with a series of rollers 27 journaled in the members 14 and adapted to engage cylindrical guide tracks 28 surrounding the shell 5. In order to rotate the shell on said rollers suitable 70 gearing is provided and as shown a gear 29 is mounted on one of the pouring spouts on the portion projecting beyond the end wall 7 and this gear engages a mating gear 30 arranged on a longitudinal shaft 31. The 75 shaft has a squared end 32 for engagement with a suitable hand crank, the latter being preferably removable when not in use. In order to hold the shell 5 in adjusted position there are the locking pins 34 extending 80 inwardly of the cradle members 14 and engaging recesses 35 in the outer shell. The pins are preferably provided with spring means 36 for normally urging the pins into said apertures and are also provided with 85 the heads 37 by which the pins may be manually withdrawn prior to adjustably rotating the shell.

The furnace is preferably heated with liquid or gaseous fuel by providing a suitable burner in the annular combustion chamber 38 between the pot and the outer shell. In order to introduce the oil and air for the burner, there are the fuel and air pipes 39 and 40 which lead from one of the 90 trunnions to the lower portion of the casing 5. The end wall 7 of this casing is preferably provided with a series of apertures 41 spaced circumferentially thereof and preferably so arranged that when the casing is 95 in one of its positions of adjustment, one of the apertures is at the lowermost portion of the combustion chamber. The oil and air pipes are led through this lowermost aperture into the combustion chamber where they 100 are united in a suitable burner 42. The combustion gases then surround the fire pot on both sides and are led completely around the same so as to secure a good heating effect. The peripheral wall 8 of the casing has a 110

series of apertures 43 spaced there around; one of which is open to permit escape of the burned products of combustion, the other apertures being normally closed. Each of the apertures 41 except the one through which the oil and air pipes are inserted are also closed by suitable removable plates 44. It is preferable to have the oil and air conduits inserted in the combustion chamber through both end walls 6 and 7, so that two burners are provided discharging toward each other. Therefore the end wall 6 is provided with a series of apertures similar to the end wall 7 and oil and air conduits 39^a and 40^a are arranged to discharge through the lowermost aperture which is in alignment with the lowermost aperture in the wall 7.

In order to permit the tilting of the furnace to pouring position, it is necessary that the oil and air conduits be permitted to move with the casing 5 about the trunnions 18 and 19. This is accomplished by providing a suitable fitting 45 on the portion of the trunnion 19 projecting beyond the bearing 12. This fitting also has connected thereto the oil and air conduits 46 and 47 respectively leading to the point of supply. It is sometimes desirable to provide mechanical power for tilting the furnace on its trunnions to pouring position and in order to adapt my construction for this purpose there is provided a motor 48 mounted on one of the standards 10. This motor is connected by a shaft 49 to a suitable gear box 50 from which a vertical shaft 51 leads to a bevel gear 52 meshing with the bevel gear 24. The motor 48 can be a reversing electric motor in which case the tilting of the furnace in either direction may be accomplished merely by actuating a suitable electric switch or if desired the gear box 50 may be provided with reversing ratios for accomplishing the same purpose.

One of the advantages of my furnace construction as above described resides in the arrangement whereby the melting pot 1 may be adjustably rotated to present different portions of its surface to the action of the molten aluminum. Thus the life of the pot is greatly extended, for only a small portion of the cylindrical portion 2 is utilized during any one heat. When adjusting the furnace to a different position the burners are removed from the combustion chamber, the locking pins 34 are withdrawn and the casing 5 then rotated manually by means of a crank fitting the squared shaft 32. As shown there are four positions of adjustment and therefore four apertures 41 in the end walls of the casing. In the new position the apertures which were previously opened are closed by cover plates and the apertures now at the lowermost portion of the furnace are opened to permit insertion of the burners. Simi-

larly the exhaust port 43 at the top of the furnace is opened while the one previously used is closed.

Figure 4 represents a modified construction in which the melting pot is not rotatably adjustable. In this case the shell 5 is directly mounted on the trunnions 53 by retaining bolts 54, while the cradle and the associated mechanism are dispensed with. Such a construction has all the advantages of the first described furnace except that of utilizing the entire periphery of the melting pot for the molten metal.

What I claim as my invention is:

1. A furnace comprising a cylindrical metallic pot having coaxial pouring apertures at opposite ends thereof, said pot having smooth uninterrupted metallic inner surfaces adapted to directly contain the molten metal, an outer casing surrounding said pot forming a heating chamber, trunnions supporting said outer casing such that the axis of said pot is normally substantially horizontal, and means for tilting said pot to discharge the contents thereof through one of said pouring apertures.

2. A melting furnace comprising a cylindrical pot having coaxial pouring apertures at opposite ends thereof, an outer casing surrounding said pot forming a heating chamber, a cradle for supporting said outer casing, trunnions supporting said cradle, and means on said cradle permitting said casing to be adjustably rotated whereby a different portion of said pot is utilized for holding the charge.

3. A melting furnace comprising a cylindrical pot, an outer casing surrounding said pot forming a combustion chamber, a cradle supporting said casing with the axis of said pot normally substantially horizontal and bearings on said cradle permitting the rotative adjustment of said casing and pot.

4. A melting furnace comprising a cylindrical pot, an outer casing surrounding said pot forming a combustion chamber, a cradle supporting said casing with the axis of said pot normally substantially horizontal, bearings on said cradle permitting the rotative adjustment of said casing about the axis of said pot, a shaft in fixed relation to said cradle, and gearing between said shaft and said casing for rotatably adjusting the latter.

5. A melting furnace comprising a cylindrical pot having coaxial pouring apertures at opposite ends thereof, a cylindrical casing surrounding said pot forming a combustion chamber, a cradle, rollers on said cradle engaging and supporting said cylindrical casing, axially aligned trunnions extending laterally of said cradle, a frame having bearings for said trunnions, means for tilting said casing about the axis of said trunnions and means for rotatably adjusting said casing relative to said cradle.

6. A melting furnace comprising a cylindrical pot, an outer casing surrounding said pot forming a combustion chamber, said casing having a cylindrical outer surface and circular end walls, a cradle supporting said outer casing, means for rotating said casing about the axis of said pot, a series of apertures spaced around said outer casing, removable closures for said apertures, and a burner extending through the lowermost aperture in said casing and arranged within said combustion chamber.

7. A melting furnace comprising a cylindrical pot, having coaxial cylindrical pouring spout at opposite ends thereof, said spouts having discharge openings of smaller diameter than said pot, an outer cylindrical casing having end walls supported on the respective spouts, said casing forming an annular heating chamber surrounding said pot, means for supporting said cylindrical casing to permit rotatable adjustment of the same about its axis, a series of inlet apertures in an end wall of said casing, a series of outlet apertures in the peripheral wall of said casing, a burner extending into said combustion chamber through an end wall aperture below said pot, and removable closures on all of the apertures in said casing except the one through which said burner is inserted and an outlet aperture arranged above said pot whereby the combustion gases from said burner are compelled to travel around said pot and exit through the upper portion of said casing.

8. A melting furnace comprising a metallic pot having a main cylindrical portion, having conical portions at opposite ends thereof provided with discharge openings of smaller diameter, said pot having smooth uninterrupted metallic inner surfaces adapted to directly contain the molten metal, an annular shell surrounding the main portion of said pot and provided on its interior with heat insulating material forming a combustion chamber, means for pivotally supporting said shell with the axis of said pot normally horizontal and means for tilting said shell and pot to pouring position.

9. A furnace for melting aluminum comprising a metallic pot of circular cross section having smooth uninterrupted metallic inside walls for directly receiving the charge and holding the molten metal, said walls being tapered inwardly at one end to form a discharge aperture of smaller cross section, an outer casing supporting said pot and surrounding the same forming a heating chamber therebetween, a frame pivotally supporting said casing with the axis of said pot normally horizontal, means for tilting said casing and pot about said pivotal support to discharge the molten metal through said discharge aperture and means for intermittently rotatably adjusting said pot relative to said frame through a partial revolution whereby a different portion of said pot is utilized for holding the molten metal in a subsequent heat.

10. A furnace for melting aluminum comprising a metallic pot having a body portion of circular cross section terminating at opposite end in heads of smaller diameter with concentric apertures therein, said pot having smooth uninterrupted inner metallic surfaces adapted to directly receive the metallic charge, an outer casing supporting the head portions of said pot and surrounding the body portion thereof forming a heating chamber therearound, a frame pivotally supporting said casing with the axis of said pot normally horizontal, means for tilting said casing and pot about said pivotal support and means for intermittently rotatably adjusting said pot relative to said frame through a partial revolution whereby a different portion of said pot is utilized for holding the molten metal.

In testimony whereof I affix my signature.
PAUL H. ROMPH.
